INVENTOR.

Rowland O. Pickin.

UNITED STATES PATENT OFFICE.

ROWLAND O. PICKIN, OF LOS ANGELES, CALIFORNIA.

ROTARY DRILL BIT.

Application filed July 19, 1920. Serial No. 397,215.

To all whom it may concern:

Be it known that I, ROWLAND O. PICKIN, a subject of the King of Great Britain, and residing at Los Angeles, in the county of 5 Los Angeles and State of California, have invented a new and useful Rotary Drill Bit, of which the following is a full and clear description, such as will enable others skilled in the art to which it appertains to make 10 and use the same.

My invention relates to improvements in rotary drill bits for the purpose of drilling holes in the earth, such as oil wells and the like, by the rotary method of drilling.

15 The principal object of the invention is to provide a more efficient and economically constructed bit for drilling holes through a varied formation.

Another object of the invention is the provision of a bit that is less inclined to deviate 20 from a straight course.

Another object of the invention is to provide a bit with a recessed cutting center, to increase the drilling speed.

25 Another object of the invention is to provide a bit with a cutting means distributed so as to maintain a constant and even keenness as the bit wears away.

Other objects and advantages of the 30 invention will be apparent as it is better understood from the following description, when considered in connection with the accompanying drawings, illustrating a preferred embodiment thereof.

35 On the drawings:

Fig. 1 is a front sectional elevation of the bit, taken through the center and on the line 1—1, Figs. 2, 3 and 4.

Fig. 2 is a side sectional elevation of the 40 bit, taken through the center, and on the line 2—2, Figs. 1, 3 and 4.

Fig. 3 is a bottom sectional view of the bit taken on the line 3—3, Figs. 1 and 2.

Fig. 4 is a bottom view of the bit.

45 Similar numerals refer to similar parts throughout the several views.

In Figs. 1, 2, 3, and 4 the cutting portion of the bit is indicated by the numeral 10, and attached to the upper portion of this 50 framework is the shank 11, upon which is the taper threaded pin 12, Figs. 1 and 2.

The cutting portion 10 of the bit consists of a tapering framework, formed into a plurality of cutting wings and in the illustrations two wings 13 and 14 are shown. The

bit is made in this manner for the reason that there is more material to be cut on the outer circumference than towards the center, and consequently the bit wears away faster on the outside than in the center. 60 This also has a tendency to keep the hole straight, as the high central portion of the hole acts as a guide, and further this central portion is more easily cut away when it comes in contact with the central cutting 65 portion 15 of the bit.

The cutting portion of the bit consists of the framework, formed by cavities 16 throughout the bit, wherever the bit comes in contact with the hole, as it is worn away 70 in service.

The cavities are formed so as to divide the framework of the bit into a series of cutting edges, and in such a manner as to prevent a series of broad sections of the walls of the 75 cavities being on the same level. In the present instance this is accomplished by arranging the cavities in inclined rows, substantially at right angles with the direction of the bore hole and across the line of travel, 80 with other cavities 16' Fig. 4, parallel to the axis of the bit, these latter being for the purpose of further reducing the material of the walls of the cavities. This form has the additional advantage of giving an even distribution of the metal of the framework, and presents little difficulty in manufacturing. 85

As an additional cutting means some of the cavities are shown to be filled with an abrasive as 17, held in position by a filler 90 18, Figs. 1, 2 and 3.

Passages 19, Figs. 2, 3 and 4 are provided for flushing out the cuttings.

In operating, the bit is turned to the right, the lowest point 20, Figs. 1 and 2 of the cutting face first begins to cut, and as this is gradually worn away, the whole face comes in contact. When this has taken place, the walls of the lowermost cavities are approximately half worn away and each successive 95 one is worn in proportion, the wall of each cavity forming a cutting edge successively, until the bit is worn out. The center of the bit also cuts away the hole as the drilling progresses. 100

It is thought that the invention and many of its attendant advantages will be sufficiently understood from the foregoing description, and it will be apparent that various changes may be made in the form, con- 110

struction, and arrangement of the parts without departing from the spirit and scope of the invention or sacrificing any of its material advantages, the form herein described being merely a preferred embodiment thereof.

I claim:

1. A rotary drill bit, having a plurality of separate wings, said wings consisting of a framework formed with inwardly extending cavities therein.
2. A rotary drill bit, having a plurality of downwardly projecting wings, said wings consisting of a framework formed with inwardly extending cavities therein.
3. A rotary drill bit, having a plurality of flatsided, downwardly projecting wings, said wings consisting of a framework formed with inwardly extending cavities therein.
- 20 4. A rotary drill bit, having a plurality of flatsided, downwardly projecting cutting portions, joined by an intermediate recessed cutting portion, all of said portions consisting of a framework formed by a series of cavities.
5. A rotary drill bit, having a plurality of outwardly and downwardly projecting cutting means joined by an intermediate recessed cutting means, said means consisting of the walls of cavities formed therein.
- 20 6. A rotary drill bit, having a plurality of outwardly and downwardly projecting cutting means, joined by an intermediate recessed cutting means, said means consisting of a framework containing a multiplicity of cutting edges, said edges being formed by cavities in said frame.
7. A rotary drill bit, consisting of a cutting frame containing cutting edges formed 40 by cavities, and projecting outwardly and

downwardly from a central cutting portion, and having a threaded pin connection.

8. A rotary drill bit, having downwardly projecting tapered cutting wings, said wings consisting of a cutting frame containing a multiplicity of cutting edges formed by cavities.

9. A rotary drill bit, having a cutting frame containing a multiplicity of cutting edges formed by parallel inwardly extending recesses throughout the cutting portion of the bit.

10. A rotary drill bit, having a cutting frame with flat sides, said cutting frame having a multiplicity of parallel cutting edges throughout the cutting portion of the frame, said edges being formed by cavities, and said cavities being filled with abrasive cutting material.

11. A rotary drill bit, having a plurality of flatsided, outwardly and downwardly projecting cutting portions joined by an intermediate cutting portion, all of said portions consisting of a cutting frame work, containing a number of cavities filled with abrasive cutting material.

12. A rotary drill bit, having a tapered cutting blade, said blade consisting of a framework formed by cavities.

13. A rotary drill bit, having a cutting blade, said blade consisting of a framework formed with a number of horizontally disposed cavities therein.

14. A rotary drill bit, having a cutting blade, said blade consisting of a framework formed with a number of vertically disposed cavities extending into the blade and having cutting edges.

ROWLAND O. PICKIN.
